UNITED STATES PATENT OFFICE.

HARRY KAUFMAN AND FRANK M. KAUFMAN, OF PHILADELPHIA, PENNSYLVANIA,
ASSIGNORS TO FRED PEARSON & COMPANY, INC., OF PHILADELPHIA, PENNSYLVANIA, A CORPORATION OF PENNSYLVANIA.

WOVEN PILE FABRIC.

1,249,769.

Specification of Letters Patent

Patented Dec. 11, 1917.

Application filed March 1, 1917. Serial No. 151,739.

To all whom it may concern:

Be it known that we, HARRY KAUFMAN and FRANK M. KAUFMAN, citizens of the United States, residing at Philadelphia, 5 county of Philadelphia, and State of Pennsylvania, have invented certain new and useful Improvements in Woven Pile Fabrics, of which the following is a specification.

Our invention relates to improvements in woven pile fabrics, the object of the invention being to provide a cut pile fabric in which the tufts, formed by the warp pile threads, are firmly secured in the backing, and present a smooth surface to the fabric 15 in the finished piece.

A further object is to provide a fabric of the character stated, in which the tufts are formed by warp pile threads in banks of six, each bank divided into two series of 20 three pile threads, with all three of each series of threads extending in the same direction, and crossing and opposite to, the direction of the three pile threads of the other series in the same bank.

25 A further object is to improve upon the fabric disclosed in Patent No. 1,169,835, granted to us February 17th, 1916.

With these and other objects in view the invention consists in certain novel features 30 of construction and combinations and arrangements of parts as will be more fully hereinafter described and pointed out in the claims.

In the accompanying drawings:

35 Figure 1 is an exaggerated view in longitudinal section, illustrating our improved pile fabric.

Figs. 2, 3, 4, 5, 6, and 7 are views similar to Fig. 1 on a somewhat reduced scale, each 40 view showing but one thread connecting the backing fabrics, and

Fig. 8 is a diagrammatic plan view of the fabric X after the pile is cut.

X and Y represent the top and bottom 45 backing fabrics which are connected by warp pile threads 1, 2, 3, and 1^a, 2^a, and 3^a respectively. All of these threads constitute a single bank divided into two series of three threads each. The threads 1, 2, and 3 represent the odd reed dents in weaving and drop 50 from the top fabric to the bottom in succession, one pick or filling thread apart, and then from the bottom fabric they extend to the top fabric in succession one pick apart.

We would have it understood that we mean 55 by the term "series of three threads", to refer to a group of three pile threads, which are successively placed transversely of the fabric and are separated, or set off from the other threads by a binding warp thread. 60

The pile threads 1^a, 2^a, and 3^a represent the even reed dents, and work just the opposite from the odd ones, or first series as above explained.

The top backing fabric X consists of binding warp threads 6, and 7, and weft threads A, B, C, D, E and F woven between the binding warp threads 6 and 7. 65

The lower backing fabric Y consists of binding warp threads 4 and 5 with weft threads A', B', C', D', E' and F' woven therein. 70

The upper and lower picks of the weft threads are simultaneously woven by the shuttles, and hence for convenience of description, these pairs of picks of the weft threads are given corresponding letters, the reference letters of the picks of the bottom fabric being primed as described. 75

While Fig. 1 illustrates two binding warp 80 threads in both upper and lower backing fabrics, it is to be understood that but a single binding warp thread is located between each series of three warp pile threads, as indicated most clearly in Figs. 2, 3, 4, 5, 6, 7 and 8 respectively.

Describing each of the warp pile threads of the bank of six, Fig. 2 illustrates the location of thread 1. This thread 1 passes over thread A, under thread B, over thread 90 C, thence down to and under thread D', thence over thread E' and under thread F'.

The thread 1^a is shown clearly in Fig. 3, where it will be noted that this thread passes under thread A', over thread B', under 95 thread C', thence up to and over thread D, under thread E, and over thread F.

In Fig. 4 it will be noted that thread 2 passes under thread A, over thread B, thence down to and under thread C', thence over 100 thread D', thence under thread E', thence up to and over thread F.

Thread 2^a is shown in Fig. 5 as passing over thread A', under thread B', up to and over thread C, under thread D, over thread 105 E, and then down to and under thread F'.

Fig. 6 shows thread 3 as passing over thread A, thence down to and under thread

B', thence over thread C', under thread D', thence up to and over thread E, and thence under thread F.

Fig. 7 shows thread 3^a passing under thread A', thence up to and over thread B, under thread C, over thread D, thence down to and under thread E', and thence over thread F'.

By comparing Figs. 2-3, 4-5, 6-7, it will be noted that the threads 1, 2 and 3 are disposed directly opposite to the threads 1^a, 2^a, and 3^a.

In weaving, the warp threads of one series indicated by 1, 2, and 3, all extend parallel to each other and in the same direction as shown in Fig. 1, while the other series of threads, 1^a, 2^a and 3^a extend in parallelism, but in the opposite direction crossing the threads 1, 2 and 3.

When the fabric is cut on a middle line between the two backing fabrics, the surface shown by the ends of the tufts will be smooth and even, and all the tufts will be firmly secured in their backing fabric.

Various slight changes might be made in the general form and arrangement of parts described without departing from our invention, and hence we do not limit ourselves to the precise details set forth, but consider ourselves at liberty to make such changes and alterations as fairly fall within the spirit and scope of the appended claims.

Having fully described our invention what we claim as new and desire to secure by Letters Patent is:

1. A pile fabric, comprising top and bottom backing fabrics, a bank of pile threads connecting the backing fabrics, each bank consisting of two series of three threads each, the threads of each series successively placed transversely of the fabric and separated or set off from the other threads by a binding warp thread, the threads of each series all extending in the same direction and crossing the three threads of the opposite series which extend in the opposite direction.

2. A pile fabric, comprising top and bottom backing fabrics, a bank of pile threads connecting the backing fabrics, each bank consisting of two series of three threads each, the threads of each series successively placed transversely of the fabric and separated or set off from the other threads by a binding warp thread, the corresponding threads of each series oppositely disposed, the threads of each series extending in parallelism in the same direction and in a di-

rection opposite to the threads of the other series, the threads of one series crossing the other at a point midway between the backing fabrics.

3. A pile fabric, comprising top and bottom backing fabrics, a bank of pile threads connecting the backing fabrics, each bank consisting of two series of three threads each, the threads of each series successively placed transversely of the fabric and separated or set off from the other threads by a binding warp thread, the threads of each series all extending in the same direction and crossing the three threads of the opposite series which extend in the opposite direction, each backing fabric consisting of weft threads and binding warp threads, a filling shot or weft thread of each backing fabric located between each pair of pile threads, and in parallelism one above the other, the said pile threads in both top and bottom fabrics woven with three of said shots, and a single binding warp thread in each backing fabric between each series of three pile threads.

4. A pile fabric, comprising top and bottom backing fabrics, a bank of pile threads connecting the backing fabrics, each bank consisting of two series of three threads each, the threads of each series successively placed transversely of the fabric and separated or set off from the other threads by a binding warp thread, the corresponding threads of each series oppositely disposed, the threads of each series extending in parallelism in the same direction and in a direction opposite to the threads of the other series, the threads of one series crossing the other at a point midway between the backing fabrics, each backing fabric consisting of weft threads and binding warp threads, a filling shot or weft thread of each backing fabric located between each pair of pile threads, and in parallelism one above the other, the said pile threads in both top and bottom fabrics woven with three of said shots, and a single binding warp thread in each backing fabric between each series of three pile threads.

In testimony whereof we have signed our names to this specification in the presence of two subscribing witnesses.
